UNITED STATES PATENT OFFICE.

JEAN BAPTISTE GUSTAVE ADOLPHE CANET, OF PARIS, FRANCE, ASSIGNOR OF ONE-HALF TO SIR JOSEPH WHITWORTH & COMPANY, (LIMITED,) OF OPENSHAW, ENGLAND.

APPARATUS FOR FACILITATING THE LOADING OF GUNS.

SPECIFICATION forming part of Letters Patent No. 417,145, dated December 10, 1889.

Application filed January 5, 1889. Serial No. 295,538. (No model.) Patented in France September 4, 1888, No. 157,389, and in England July 1, 1887, No. 9,375.

To all whom it may concern:

Be it known that I, JEAN BAPTISTE GUSTAVE ADOLPHE CANET, civil engineer, a citizen of the Republic of France, and a resident of 5 Paris, France, have invented new and useful Improvements in Apparatus for Facilitating the Loading of Guns, (for which I have obtained patents in Great Britain, No. 9,375, bearing date July 1, 1887, and in France, No. 10 157,389, bearing date September 4, 1888,) of which the following is a specification, reference being had to the accompanying drawings.

My invention relates to apparatus for facilitating the loading of guns, and is chiefly 15 designed to afford the means whereby the loading of a gun mounted upon a rotating platform or turn-table may be effected in any position to which the gun may be trained or 20 while it is being trained. For this purpose I employ a lever which is pivoted to the said platform or turn-table in such a manner that it can be turned upon its pivot in a vertical plane passing through the longitudinal axis 25 of the gun. The free end of this lever is adapted to receive a projectile or powder-charge, and suitable means are provided for turning the said lever about its pivot and thus raising the said projectile or powder- 30 charge into position behind the breech of the gun and in line with the bore thereof, so that it can be rammed therein by hand or by any suitable mechanism.

In the accompanying drawings, Figure 1 is 35 a plan illustrating one form of my improved apparatus, part of the hand-rail being removed to show more clearly the parts beneath it; Fig. 2, a side elevation, partly in vertical longitudinal central section; and Fig. 3 is a rear 40 elevation. Fig. 4 is a side elevation, partly in vertical longitudinal section, showing the charge-elevating lever in the position to which it is raised to permit the ramming of the projectile into the gun; and Fig. 5 is a side elevation, partly in vertical longitudinal section, 45 illustrating another form or modification of my improved apparatus.

A is the base-plate or racer and center pivot; B, the rotating platform or turn-table.

C is a rocking lever, which is fixed upon a 50 shaft C', supported in bearings formed or fixed on the said platform or turn-table.

D is a charge-carrier or cradle which is jointed or pivoted at D' to the extremity of the lever C.

A cam E is fixed upon the shaft C', and is arranged in combination with a chain F, connected with a rod G, which acts upon and is acted upon by a so-called "Belleville" spring H or other suitable spring incased in a box J, 60 which is pivoted at its rear end J' to the turn-table or under carriage. The spring H is designed, in connection with the cam E, to counterbalance the lever C and carrier D, and thus equalize, or tend to equalize, the force 65 required for raising and lowering them by resisting their descent and diminishing the resistance to their ascent, so that when a charge or projectile is in the carrier D the resistance to be overcome in raising the said carrier will 70 be only that due to the weight of the said charge or projectile. The cam E is, moreover, so formed that in the descent of the lever C the chain F will be wound thereon and the spring H thus compressed, and as the lever descends the mechanical advantage afforded by the cam in favor of the spring will 75 be increased.

Motion is imparted to the shaft C' by means of a shaft K, provided with a crank or handle 80 K', and having fixed thereon a pinion L, Figs. 1 to 4, or a worm M, Fig. 5, which pinion or worm is geared with a toothed segment N, fixed on the said shaft C'; or the shaft C' is provided with other suitable means for operating it.

P is a strap fitted with a wooden block P', upon which the lever C rests when in its lowermost position.

I can, if desired, employ in place of the 90 spring H a counter-weight or other suitable means for counterbalancing the rocking lever C, for the purpose above specified.

What I claim is—

1. The combination of a rocking arm or lever carried by the platform or turn-table of a gun-mounting and arranged to be moved in a vertical plane extending through the longi-

- tudinal axis of the gun, and a charge-carrier or cradle secured to the free end of the said arm or lever, so that the said carrier or cradle when lowered will be in a convenient position outside the mounting to receive the projectile or powder-charge, but when raised will support the said projectile or powder-charge in line with the bore of the gun, substantially as and for the purpose above specified.
- 10 2. The combination of a rocking lever C, pivoted to the platform or turn-table of a gun-mounting and arranged to be moved in a vertical plane extending through the longitudinal axis of the gun, and a charge-carrier or cradle D, secured to the free end of the said arm or lever, so that when lowered it will be suspended in a convenient position outside the mounting to receive a projectile or powder-charge, but when raised it will support
- 15 the said projectile or powder-charge in the loading position behind the breech of the gun, substantially as and for the purpose above specified.
3. The combination, with a gun-mounting, of a rock-shaft C', carried thereby, an arm or lever C, fixed upon the said shaft, and a charge-carrier or cradle D, secured to the free end of the said arm or lever, substantially as and for the purpose above set forth.
- 20 4. The combination, with a rocking arm or lever C, carried by the platform or turn-table of a gun-mounting, and a charge-carrier or cradle D, secured to the said arm or lever, of a spring or its equivalent for counterbalancing the said lever and cradle, substantially as and for the purpose above specified.
- 25 5. The combination of a rock-shaft carried by the platform or turn-table of a gun-mount-

ing, an arm or lever fixed on the said shaft, a charge-carrier or cradle secured to the said arm or lever; a cam fixed upon the said shaft, a counterbalancing-spring, and a chain connected at one end with and arranged to be wound upon the said cam and connected at its other end with the said spring, substantially as and for the purposes set forth.

6. The combination of a rock-shaft C', carried by the platform or turn-table of a gun-mounting, an arm or lever C, fixed on the said shaft, a charge-carrier or cradle D, secured to the said arm or lever, a toothed segment N, fixed on the said shaft C', and a shaft K, provided with a crank-handle and geared with the said toothed segment, substantially as and for the purpose set forth.

55 7. The combination of a rock-shaft C', carried by the platform or turn-table of a gun-mounting, an arm or lever C, fixed on the said shaft, a charge-carrier or cradle D, secured to the said arm or lever, a cam E, fixed on the said shaft, a counterbalancing - spring H, a chain F, connected at one end with and arranged to be wound upon the said cam and connected at the other end with the said spring, a toothed segment N, fixed on the said shaft C', and a shaft K, provided with a crank-handle and geared with the said toothed segment, all substantially as and for the purposes set forth.

In testimony whereof I have hereunto signed my name in the presence of two subscribing witnesses.

JEAN BAPTISTE GUSTAVE ADOLPHE CANET.
